R. L. WILCOX.

COMPENSATING MECHANISM.

FILED MAY 22, 1922.

Inventor
Richard Lester Wiley
By George E. May
Atty.

UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

COMPENSATING MECHANISM.

Application filed May 22, 1922. Serial No. 562,923.

To all whom it may concern:

Be it known that I, RICHARD LESTER Wilcox, a citizen of the United States, residing at Waterbury, in the county of New Haven and State of Connecticut, have invented certain new and useful Improvements in Compensating Mechanisms, of which the following is a specification, reference being had therein to the accompanying drawings.

10 This invention relates to compensating mechanism particularly as applied to heading or upsetting machines, although not limited thereto.

It is the object of this invention, among other things, to provide a simple and efficient device so associated with the means for operating a movable part, such as a punch slide, that variations in the position of the movement thereof may be made without 20 requiring adjustment of its operating means.

Among other aims and objects of the invention may be recited the provision of a device of the character mentioned with a view to compactness, in which the number 25 of parts are few, the construction simple and both efficiency and operation high.

The details and arrangement of parts will be apparent from an inspection of the accompanying drawings in connection with 30 the description hereinafter contained and wherein a preferred embodiment of the invention is disclosed for the purpose of imparting an understanding of the same.

In the drawings:

35 Figure 1 is a side elevation of the form of my mechanism as applied to a heading or upsetting machine, the portion of the latter immediately adjacent thereto being also shown; and

40 Figure 2 is a side elevation, partly in section, of the connecting rod and of several of the associated parts.

It is necessary from time to time in heading or upsetting machines to vary the relative position of the slide upon the gate. This has required in the past an adjustment of the stop mechanism connected with the gate and slide and also an adjustment of the parts that actuate the rock shaft and impart 45 movement to the slide. The stop devices

connected with the slide and gate are so located as to be conspicuous and within easy reach of the operator, hence are always manipulated for adjustments; while the parts associated with the rock shaft are usually so 55 located as not to be so readily accessible and manipulation thereof is frequently overlooked. When this occurs the relative movement of the punch slide is both uncertain and inaccurate and undue strain is placed 60 upon the parts which frequently break.

With my improved mechanism it is only necessary to obtain the adjustment of the punch slide by the stops and the parts that operate the rock shaft automatically adjust 65 themselves.

In the drawings wherein like characters of reference designate corresponding parts in the several figures, 10 is a portion of the frame of a heading or upsetting machine, 11 70 the gate that has a reciprocatory movement therein, 12 the rock shaft journaled in the bearings 13 connected with the frame 10, and 14 the punch slide, to which is adjustably secured the punch block 15 having the 75 punches 16 therein. This slide is movably mounted in the front end of the gate 11.

Connected with the rock shaft 12 are arms 17 and 18, the former of which is connected with the punch slide 14 through the stud 19 80 in a manner well known to the art. The source of power to operate the punch slide is derived from the shaft 20 upon which is a cam 21.

The up position of the punch slide 14 in 85 relation to the gate is limited by the nuts 44 threaded on the stud 45 fixed in the gate 11, and passing through the slide lug 46. Its down position is limited by the stop screw 47 which is threaded through the lug 90 46 and contacts with the top of the gate. This method of the adjustment of the stroke and position of the punch slide is old and the one always utilized by the operator, sometimes, however, in the types of headers heretofore made, to the neglect of the rock shaft operating mechanism and necessary to fully accommodate the punch slide in its adjusted limits.

100 All of the parts above described as well

as the operation thereof are now well known in the header art and require no further description herein.

5 The numeral 22 designates the connecting rod upon which is rotatably mounted a cam roll 23 that travels in the path 24 of the cam 21 and having a yoke end 25, between the walls of which is a slide block 26 that is journaled upon the shaft 20.

10 The end of the connecting rod 22 opposite to the yoke end 25 is slotted at 27 and the open end thereof covered by the cap 28 secured in position by bolts 29 or similar means.

15 Movable between the walls of the slot 27 is the slide block 30 projecting laterally from two sides of which are the rods 31 and 32, the former extending through an opening 33 and a transverse wall of the connecting rod 22 and the other through an opening 34 in the cap 28.

20 Surrounding the rod 31 is a coil spring 35 and a similar spring 36 surrounds the rod 32, these being held in position and under 25 variable tension by the nuts 37 and washer 38. I have shown in the drawings these rods 31 and 32 as being made integral with the slide block 30, but obviously either one or both may be independent thereof and secured thereto in any desired manner.

25 Fixed to the outer end of the arm 18 by the nut 39 is the stud 40 which projects through the slide block 30 and is provided with a washer 41 and nut 42 on its outer end. A collar 43 upon the stud 40 prevents endwise movement of the slide block 30 upon the stud in one direction.

30 Motion is imparted to the slide 14 from the shaft 20 through the connecting rod 22, slide block 30, stud 40, arm 18, rock shaft 12, arm 17 and stud 19 my means of the engagement of the cam roll 23 with the cam groove 24.

35 As shown in the drawings the punch slide 45 14 is in its down position and the connecting rod 22 is in its extreme outer position relatively to the shaft 20 and springs 35 and 36 are so adjusted that no tension is applied thereto. However, a variation of the relative position of the slide 14 through the stop screw 47 or nuts 44 will also vary the outer extreme positions of the arm 18 and stud 40.

40 As the length of the stroke of the connecting rod 22 is not variable any change in the 55 extreme positions of the stud 40 in either direction are accommodated by the compression of either one of the springs 35 or 36 depending upon the direction of such change.

45 Minor changes and alterations may be made within my invention aside from those herein suggested and I would therefore have it understood that I do not limit myself to the exact construction herein shown and described, but claim all that falls fairly with-

5 in the spirit and scope of the appended claims.

What I claim as new and desire to secure by Letters Patent, is:

1. In combination with a supporting member, of a slide mounted therein; means for adjusting the position and stroke of said slide in relation to said supporting member; a rotary member; a rock member between said slide and rotary member; connection means between said rotary member and rock member having yielding mechanism forming part thereof, which yielding mechanism is substantially parallel with the line of travel of said connection. 70

2. In combination with a supporting member, of a slide mounted therein; means for adjusting the position and stroke of said slide in relation to said supporting member; a rotary member; a rock member between 80 said slide and rotary member; a connecting rod having an operative engagement with said rotary member and also with said rock member; and yielding mechanism associated with said connecting rod operative in a path 85 substantially parallel with that of said connecting rod. 90

3. In combination with a supporting member; of a slide mounted therein; means for adjusting the position and stroke of said 95 slide in relation to said supporting member; a rotary member; a rock member between said slide and rotary member; connection means between said rotary member and rock member; and means that automatically yield 100 to accommodate any over-throw of said rock member in either direction and actuated in a path substantially parallel with the direction of movement of said connection means. 105

4. In combination with a supporting member, of a slide mounted therein; means for adjusting the position and stroke of said 110 slide in relation to said supporting member; a rotary member; a rock member between said slide and rotary member; a laterally projecting part associated with said rock member; a connection between said rotary member and laterally projecting part; and yielding means associated with said connection 115 and laterally projecting part and actuated in a path substantially parallel with the direction of movement of said connection. 120

5. In combination with a supporting member, of a slide mounted therein; means for adjusting the position and stroke of said slide in relation to said supporting member; a rotary member; a rock member between 125 said slide and rotary member; connection means between said rock member and rotary member having a pivot engagement with said rock member; and yielding mechanism associated with said connection means and pivot that is actuated in a line substan- 130

tially parallel with the direction of movement of said connection means.

6. In combination with a supporting member, of a slide mounted therein; means for 5 adjusting the position and stroke of said slide in relation to said supporting member; a rotary member; a rock member between said slide and rotary member; connection means between said rock member and rotary 10 member having a pivot engagement with said rock member; and yielding means upon opposite sides of said pivot, connected therewith and substantially parallel with said connection means.

15 7. In combination with a supporting member, of a slide mounted therein; means for adjusting the position and stroke of said slide in relation to said supporting member; a rotary member; a rock member between 20 said slide and rotary member; a connecting rod having an operative engagement with said rotary member and also with said rock member; and a yielding member upon each 25 of two sides of the point of engagement of said connecting rod with said rock member, which are actuated in a path substantially parallel with that of the movement of said connecting rod.

8. In combination with a supporting member, of a slide mounted therein; means for 30 adjusting the position and stroke of said slide in relation to said supporting member; a rotary member; a rock member between said slide and rotary member; a pivot member 35 associated with said rock member; a connecting rod having an operative engagement with said rotary member and with said pivot member; yielding means associated with said pivot member upon opposite

sides thereof and operative in the same 40 plane, which is substantially parallel with the direction of movement of said connecting rod.

9. In combination with the supporting member, of a slide mounted therein; means 45 for adjusting the position and stroke of said slide in relation to said supporting member; a rotary member; a rock member between said slide and rotary member; a pivot member 50 connected with said rock member; a connecting rod having engagement with said rotary member and a sliding engagement with said pivot member; spring supporting means connected with said pivot member and projecting upon opposite sides thereof 55 forming extension of each other; and a spring upon each of said spring supporting means which yield by any excess movement of said rock member.

10. In combination with the supporting member, of a slide mounted therein; means 60 for adjusting the position and stroke of said slide in relation to said supporting member; a rotary member; a connecting rod having 65 an operative engagement at one end with said rotary member and at the other end with a pivot member associated with said rock member; means associated with said rod for closing that end thereof adjacent to said pivot member; a rod projecting upon 70 each side of said pivot member and in line with each other; and a spring surrounding each of said rods which yield during any over-throw of the stroke of said rock member.

In testimony whereof, I have hereunto 75 affixed my signature.

RICHARD LESTER WILCOX.
